No. 885,081.

PATENTED APR. 21, 1908.

E. POTTER.
CUTLERY KNIFE HOLDER.
APPLICATION FILED JAN. 10, 1907.

Fig. 1.

UNITED STATES PATENT OFFICE.

ERNEST POTTER, OF SOUTH MERIDEN, CONNECTICUT, ASSIGNOR TO HEMMING BROTHERS,
OF NEW HAVEN, CONNECTICUT.

CUTLERY KNIFE-HOLDER.

No. 885,081.

Specification of Letters Patent. Patented April 21, 1908.

Application filed January 10, 1907. Serial No. 351,713.

To all whom it may concern:

Be it known that I, ERNEST POTTER, a citizen of the United States, and a resident of South Meriden, in the county of New Haven, 5 and State of Connecticut, have invented certain new and useful Improvements in Cutlery Knife-Holders, of which the following is a specification.

My invention relates to an improved knife 10 holder adapted for use in connection with cutlery grinding and cutlery polishing machines. While capable of holding knives of every description, it is particularly adapted for holding "stub" and "round tang" knives.

To enable others to understand my invention, reference is had to the accompanying drawings in which:

Figure 1— represents an upper plan view of the holder showing the gripping jaws open 20 Fig. 2— is a side elevation of the holder: Fig. 3— a section on —a a— of Fig. 1: Fig. 4— is a broken section of the holder and knife blade therein with the jaws closed.

1— represents the base of the holder, 25 which base may be attached to the reciprocating carriage or slide of a cutlery grinding or polishing machine, or it may be an integral part of the same.

2— is a bed or support for the face of the 30 blade —3—, and is attached to the base by screws —4—. This bed can, if desired, form an integral part of the base —1—.

5— is a ledge or flange rising from the bed to form a support for the back of the knife 35 blade.

6— is the stationary jaw having the rounded lip —6^a— and curved recess or depression —6^b— adapted to receive the neck —3^a— of the blade.

40 7— is the movable jaw pivotally supported on the bolt —8— and having a corresponding lip —7^a— and depression —7^b—.

9— is a bracket secured by the screw —10— to the stationary jaw —6—.

45 11— is a stud projecting from the bracket to form a bearing on which the hub of the handle lever —12— is journaled.

13— is a spring cam secured to the handle lever by the screw —14— whose free end is 50 located between the inner face of the hub of the handle lever and the outer face of the bracket —9—, which free end is provided with the hole —15— (Fig. 3) so as to loosely

embrace the stud —11—. 16— are jam nuts on the outer end of this stud to regulate the 55 tension on the cam —13—.

17— & —18— are adjustable set screws projecting through the jaws whose points are adapted to engage the tang —3^b— of the knife when the knife is in the grip of the jaws, 60 and —19— and —20— are jam nuts for said screws.

Operation. The knife blade is placed on the support —2— when the jaw —7— is in open position as shown at Fig. 1. The handle lever is then rotated in the direction of arrow —b— of Fig. —2— until it strikes against the stop —22—. Turning the handle lever in the direction as stated, will bring the outer face of the cam forcibly against the 70 outer face of the jaw —7— and the closing of this jaw will carry the knife blade against the ledge —5— and clamp the neck of the blade firmly as shown at Fig. 4. The set screws —17— and —18—, being previously 75 adjusted, grip the tang so as to balance the grip of the jaws and also keep the blade level during the operation of grinding or polishing. When the handle lever is thrown around against the stop —22—, the spring —23— 80 will open the jaw —7—, which open movement is limited by the contact of the opposite end of the jaw with the stop pin —24—.

Having thus described my invention, what I claim as new and desire to secure by Letters Patent is:

1. In a knife holder of the character described, a support for the blade, jaws adapted to grip the neck of the knife, one of said jaws stationary and the other movable, adjustable 90 set screws adapted to engage the tang of the knife, means for operating the movable jaw, for the purpose set forth.

2. In a knife holder of the character described, a support for the blade, jaws adapted 95 to grip the neck of the knife, one of said jaws movable and the other stationary, adjustable means for engaging the tang of the blade, a handle lever, a support therefor, a spring cam adapted to contact with the movable jaw, 100 for the purpose set forth.

3. In a knife holder of the character described, a support for the blade, jaws adapted to grip the neck of the knife, adjustable means on said jaws for gripping the tang of 105 the knife, one of said jaws stationary and the

other movable, a handle lever, a bearing on which the handle lever is journaled, a support for said bearing, a spring cam secured to said handle lever and adapted to engage with 5 the movable jaw when the handle lever is rotated to close said jaw, for the purpose set forth.

Signed at So. Meriden in the county of New Haven and State of Connecticut this 14 day of Dec. A. D. 1906.

ERNEST POTTER.

Witnesses:

GUSTAVE HEMMING,
THOMAS A. BENHAM.
